UNITED STATES PATENT OFFICE.

CHARLES MARTIN, OF MANCHESTER, IOWA.

VIOLIN.

1,278,707.

Specification of Letters Patent. Patented Sept. 10, 1918.

Application filed May 21, 1918. Serial No. 235,834.

To all whom it may concern:

Be it known that I, CHARLES MARTIN, a citizen of the United States, residing at Manchester, in the county of Delaware and State of Iowa, have invented certain new and useful Improvements in Violins; and I do hereby declare the following to be a full, clear, and exact description of the invention, such as will enable others skilled in the art 5 to which it appertains to make and use the same.

My invention relates to violins.

The primary object of this invention is to improve the construction, and consequently the tone and expression of violins. 15

A secondary object is to dispense with the usual sound post in violins.

With these objects in view the invention consists in the improved construction, arrangement and combination of the parts of 20 an instrument of the character specified, which will be hereinafter fully described and afterward specifically claimed.

In order that the construction and operation thereof may be readily comprehended, I have illustrated an approved embodiment 25 of my invention in the accompanying drawings, and will now proceed to fully describe the same in connection with said drawings, in which

Figure 1 represents the top or belly of a violin, the finger board or neck being shown partly broken away and interior parts being shown in dotted lines,

Fig. 2, a sectional view of the instrument taken on the central longitudinal, vertical plane indicated by the broken line 2—2 of Fig. 1, and

Fig. 3, a sectional view on the transverse vertical plane indicated by the broken line 3—3 of Fig. 1.

Like reference characters mark the same parts in all of the figures of the drawing.

Referring specifically to the drawing, 5 indicates the top or belly of the instrument, 6 the bottom or back thereof, and 7 the finger board projecting from the neck 8 centrally over the belly of the instrument, all of these parts being of any well known 45 material and form, and the belly being provided with the usual sound holes 9 of the well known form of the long letter f.

Usually a sound post has been used in violins fitted to stand vertically, inside the 55 body of the instrument between the back and belly but I have dispensed with this

usual well known part and in lieu thereof I provide bars 10 and 11 of the form shown plainest in Fig. 2, being, in an ordinary instrument, about $7\frac{1}{2}$ inches long, $\frac{1}{8}$ inch thick, 60 and 1 inch wide, although these dimensions may be varied in different instruments as experience, experiment or judgment may dictate.

These bars I place under the belly, inside 65 the instrument, in position to form an elongated V with the apex toward the neck of the instrument, and glue the ends 12 of the upper edges for the extent of approximately half an inch to the under or inner 70 side of the belly.

Holes 13 and 14 are formed through the body of the belly each positioned at one side of approximately the center of the area thereof to lie directly over one of the bars 75 10 and 11. Within these holes two cylindrical posts 18 and 19 are placed which rest upon the upper edges of the bars 10 and 11 and project through the holes slightly above the outer face of the belly and are arranged 80 to support the feet 15 and 16 of the bridge 17. It is the purpose of this invention to dispose the holes 13 and 14 at each side of approximately the center of the belly as shown in Fig. 1, where the line 3—3 passes 85 through these holes at a right angle to the line 2—2 and thus divides the belly into two parts of substantially equal area. By such a division of the surface of the belly each quarter of the instrument would be of practically the same area, as the posts disposed in the holes lie at equal distances on each 90 side of substantially the exact center of the surface as before described.

This arrangement distributes the weight 95 or pressure of the bridge upon somewhat widely separated points in the belly, being the forward and rearward ends of the bars where they are secured to the belly, and after long continued experiment I found 100 that a much softer pleasing tone is produced than with instruments provided with the usual sound post.

The utility and simplicity of my invention will be evident from the foregoing and 105 I desire to be understood that changes and variations may be made from the specific construction described, without departing from the spirit and scope of the invention.

Having thus fully described my invention, 110 what I claim as new and desire to secure by Letters Patent of the United States is:

1. A violin comprising the usual body having belly, back and bridge, provided with holes in the belly, short posts projecting through said holes in position to receive and support the feet of the bridge, and elongated supports for said posts secured to the inner face of said belly.
2. A violin comprising the usual body, having belly, back and bridge, provided with holes in the belly, short posts projecting through said holes in position to receive and support the feet of the bridge, and supports for said posts inside the body, comprising bars secured to the inside of the belly and passing under said holes.
3. A violin comprising the usual body having belly, back and bridge, provided with holes in the belly, short posts projecting through said holes in position to receive and support the feet of the bridge, and supports for said posts inside the body comprising bars secured at their extremities to the inside of the belly and passing under said holes.
4. A violin comprising the usual body having belly, back and bridge, provided with holes in the belly, short posts projecting through said holes in position to receive and support the feet of the bridge, and supports for said posts inside the body comprising two bars secured at their extremities to the inside of the belly in position to form an elongated V, and passing under said holes.

with holes in the belly, short posts projecting through said holes in position to receive and support the feet of the bridge, and supports for said posts inside the body comprising two bars secured at their extremities to the inside of the belly in position to form an elongated V, and passing under said holes.

In testimony whereof I have signed my name to this specification in the presence of two subscribing witnesses:

CHARLES MARTIN.
